FIG. 4

INVENTOR
EDWARD SPICER.

By *Robert L. Hough*
Atty.

UNITED STATES PATENT OFFICE.

EDWARD SPICER, OF VANCOUVER, BRITISH COLUMBIA, CANADA.

COVERING FOR BOILERS, PIPES, AND THE LIKE.

Application filed November 11, 1920. Serial No. 423,420.

To all whom it may concern:

Be it known that I, EDWARD SPICER, a subject of the King of Great Britain, and a resident of the city of Vancouver, in the 5 Province of British Columbia, Canada, have invented certain new and useful Improvements in Coverings for Boilers, Pipes, and the like, of which the following is a specification.

10 My invention relates to improvements in covering for boilers or other analogous purposes, and the object of my invention is to devise a means whereby the asbestos covering usually employed may be easily applied and the use of which prevents heat from the boiler passing through to the outside of the covering or to the metal lining which may be used to cover the asbestos so that the outer surface of the cover is maintained at all times cool.

I attain this object by the means illustrated in the accompanying drawings in which—

Fig. 1 is an outside elevation showing 25 the boiler covered.

Fig. 2 is an outside elevation with the front part of the outer lining cut away.

Fig. 3 is a perspective view of the band.

Fig. 4 is a fragmentary view of a modification of the invention.

Similar figures of reference indicate similar parts throughout the several views.

In covering boilers according to the present invention metal bands, indicated by the 35 numeral 1, are employed and in hot water boilers such as is shown in the drawings three such bands are preferably employed, one near the upper end of the boiler, one about the midheight, and one near the lower 40 end and these bands are provided with inwardly turned members 2 of triangular shape, these members being formed out of the band itself by making two cuts along the edges of the band at the designated positions and then bending inwardly the cut portion to extend at right angles to the inner periphery of the band, the inner points of the members being sharp on account of their 45 triangular shape. There are two series of 50 members 2 in each band, one along the upper edge and one along the lower, and the bands are each divided, as at 3, the divided ends being turned inwardly at right angles and provided with holes through

which a bolt 4 may be passed to draw the ends of the band together, a hole 5 being also formed in the band so that a screwdriver or other similar tool may be passed through to hold the head of the bolt from turning. When the bands are in place, sheets of asbestos, indicated by the numerals 6, 7, 8 and 9 are placed around the boiler 10, the ends of which sheets fit within the bands 1 and rest on the members 2, and these sheets are then enclosed within 65 sheet metal covers 11 and 12 having divided ends 13 and 14, one end, 13, being doubled over on itself to form a groove 15 adapted to receive the opposite end 14, and the covers are provided with opposed lugs 16 so that 70 they may be drawn together and secured by the bolts 17.

It will thus be seen that there is then a space 18 left between the asbestos sheets and the metal covers which constitutes an air space 75 so that the heat does not pass to the covers from the asbestos, nor does it pass to the covers from the bands since these are held clear of the boiler by the members 2, and as the members 2 themselves bear on the 80 boiler only at their sharp pointed ends, the heat cannot travel along the members to the bands, and thus the outside covers are always maintained cool.

The upper end of the boiler may be cov- 85 ered with any suitable form of cover, such as indicated at 19 in Fig. 2.

While I have described and illustrated the carrying out of the invention by the means of the bands 1 it may be stated that 90 instead of these separate bands a piece of expanded metal or wire mesh, in one or more sections to suit the length of the boiler, may be used, a fragment of such metal being shown in Fig. 4 and indicated by the 95 numeral 20, and which metal is provided on its inner face with pointed members 21 similar to the members 2 already described. In this case the metal sheet is wrapped around the boiler with the pointed members resting 100 on the shell and the asbestos is then plastered on the metal to cover the same to a suitable thickness. As the asbestos covering does not then bear on the boiler the heat does not pass through to the outside of the covering to be appreciably felt, nor does it heat 105 the metal unduly, since only the sharp point of each member 21 touches the shell,

thus preventing the pointed members, and consequently the metal 20, from becoming unduly hot.

What I claim as my invention is:—

- 5 1. The combination of a boiler, a series of spaced bands surrounding the same, upper and lower sets of projections extending inwardly from each band into engagement with the boiler to space the body of the band therefrom, said projections being disposed inwardly of the 25 upper and lower edges of the band, and non-conducting material enveloping the boiler between the bands and held in place by engagement beneath the edges of the latter.
- 10 2. The combination of a boiler, a series of spaced bands surrounding the same, 30 retaining band for non-conducting boiler coverings comprising an annular body provided with pairs of incisions extending inwardly from the upper and lower edges of the band, the material between the incisions 35 of each pair being bent inwardly to provide upper and lower sets of boiler engaging prongs disposed inwardly of the upper and lower edges of the bands.
- 15 3. As a new article of manufacture, a 40
- 20

projections extending inwardly from each band into engagement with the boiler to space the body of the band therefrom, said projections being disposed inwardly of the 25 upper and lower edges of the band, and non-conducting material enveloping the boiler between the bands and held in place by engagement beneath the edges of the latter.

3. As a new article of manufacture, a 30 retaining band for non-conducting boiler coverings comprising an annular body provided with pairs of incisions extending inwardly from the upper and lower edges of the band, the material between the incisions 35 of each pair being bent inwardly to provide upper and lower sets of boiler engaging prongs disposed inwardly of the upper and lower edges of the bands.

Dated at Vancouver, B. C., this 1st day 40 of November, 1920.

EDWARD SPICER.
